METHOD AND APPARATUS FOR MACHINING
CARBURETOR PORTS

William Frank Eipl and James L. Greene, Rochester, N.Y., assignors to General Motors Corporation, Detroit, Mich., a corporation of Delaware

Filed Aug. 11, 1960, Ser. No. 48,862

3 Claims. (Cl. 77—32.2)

This invention relates to a method and apparatus for accurately controlling a machining operation, and more particularly, to a method and apparatus for accurately locating and machining carburetor ports relative to a predetermined reference position on the carburetor.

Carburetors are conventionally formed from a plurality of housings including a throttle valve housing in which an induction passage is provided and in which a plurality of fuel and air passages are also provided. A conventional carburetor contains a movable throttle valve within the induction passage and a throttle valve control shaft extending therethrough. Theoretically, the air and fuel passages provided in a carburetor should be located in a predetermined manner relative to position or positions of the throttle valve and relative to various operating conditions. The use of mass production techniques in the manufacture of carburetors often results in dimensional variations from carburetor to carburetor in the location of the throttle valve and throttle valve shaft relative to the machined surfaces of the throttle valve housing. In previous practice, air and fuel passages, such as an idle air bypass and an idle fuel bypass, have been located with reference to one of the machine surfaces on the throttle valve housing. Thus, the accuracy of the location of such passages relative to the throttle valve has depended on production dimensional control and normal dimensional variations in production throttle valve housings.

The principal object of this invention is to provide an improved method and apparatus for accurately locating machining apparatus relative to a reference surface on a workpiece. A further object is to provide an improved method and apparatus for accurately locating carburetor holes relative to the throttle valve thereof. Another object is to provide apparatus adapted for mass production of carburetors which have accurate and consistent dimensional characteristics. Still another object is to provide means for accurately positioning a carburetor throttle valve housing relative to machining apparatus so that each housing so positioned is exactly located relative to the throttle valve carried thereby regardless of dimensional variations of the parts and surfaces of the housing.

Other objects and advantages will become apparent by a reference to the accompanying drawing illustrating a preferred embodiment of the invention and wherein:

FIGURE 1 is a side elevational view of the apparatus of this invention;

FIGURE 2 is a plan view, partly in section, of the apparatus shown in FIGURE 1;

FIGURE 3 is an enlarged detail view, partly in section, of a portion of the apparatus shown in FIGURE 1 prior to a machining operation; and,

FIGURE 4 is an enlarged detail view, partly in section, of the apparatus shown in FIGURE 1 after a machining operation.

Referring now to FIGURE 1, a suitable frame or table 10 supports the apparatus of this invention adjacent to conventional machinery capable of machining holes within a carburetor throttle valve housing 12. The throttle housings to be machined are provided with an induction passage 14, a throttle valve 16, a throttle shaft 18 which extends outwardly on opposite sides of the

2

induction passage and a control lever 20 as shown in FIGURE 2. A machining head 22 is shown adjacent the throttle housing 12 and may be connected to a machine of any conventional design, such as a drilling machine or an electric discharging machine. A lower carriage or slide 24 having a front portion 26 and a rear portion 28 is slidably supported on a suitable guide means in a conventional manner. Suitable motor means 30 is drivingly connected to the slide 24 by any suitable means such as a threaded shaft 32 which is connected to a conventional drive nut arrangement on the rear slide portion 28. The motor means 30 is actuatable through conventional circuitry (not shown) to cause reciprocation of the slide 24. An upper carriage or slide 34 is slidably mounted on suitable guide means on the front portion 26 of the slide 24. Suitable motor means 36 is mounted on the rear portion 28 of the lower slide and is drivingly connected to the upper slide 34 through a conventional variable speed clutch and brake 38 by shaft members 40, 42. A drive nut arrangement 44 is secured to the slide 34 and is suitably connected to the shaft 42. A conventional clamping cylinder 46 is mounted on a bracket 48 on the rear end of the upper slide 34 and a cylinder rod 50 is provided with a carburetor clamp 52 on its outer end. The carburetor clamping jaw and support 52 is slidably supported by a guide block 54 on a guide plate 56 fixed to the bracket 48.

A clamping bracket 58 is fixed to the front end of the upper slide 34 and spaced forwardly of the cylinder bracket 48. A throttle housing positioning and clamping plate 60 is fixed to the bracket 58 in alignment with the jaw clamp 52 and includes a guide shaft 62 adapted to be received within the induction passage 14 of the throttle housing 12. As shown in FIGURE 4, a portion 64 of the guide shaft 62 is relieved to accommodate movement of the throttle valve 16 from a closed position as shown in FIGURE 3 to the open position as shown in FIGURE 4.

The control lever 20 is attached to an actuator 66 which exerts a throttle valve closing force on the control lever 20 due to a weight 68 supported over a pulley means 70. Any other suitable device, such as a spring mechanism, may be utilized to provide the necessary bias on the throttle control lever 20. The other end of the throttle shaft 18 is actuatable connected to a cylinder rod 72 of an actuating cylinder 74 through any suitable coupling means 76 for a purpose to be hereinafter described. The cylinder 74 is mounted on the bracket 58 so that the cylinder rod 72 may be actuated into engagement with the end of the throttle valve shaft 18.

A gauge bracket 78 is fixed to the support frame 10 and supports a conventional indicating gauge device 80 having an indicating dial 82 and a movable probe 84. The indicating gauge is utilized as a locating gauge and is hereinafter referred to as such. The probe 84 is adapted to extend through the bracket 58 and the guide shaft 62 into the induction passage 14 for engagement with the throttle valve 16. The locating gauge 80 is adjustably fixed to the bracket 78 for vertical and horizontal adjustment. The locating gauge includes a plurality of conventional circuit controlling contacts (not shown) which are engageable by the movable probe 84 at predetermined positions. A collecting pan 86 may be provided beneath the valve housing 12 to collect dielectric fluid if an electric discharge machining process is used. Suitable circuit controlling limit switches 88, 90 and 92 are provided to control positioning of the slide members and are actuatable by adjustable contacts 94, 96 carried by the slide 24.

Operation

It is to be understood that suitable conventional circuitry is provided to control the actuation of the afore-

described mechanism. At the beginning of each work cycle, the apparatus is positioned at the extreme right-hand side of the table 10 as viewed in FIGURE 1. The carburetor throttle valve housing 12 is suitably mounted on the carburetor clamping jaw and support 52 by the machine operator and the throttle valve control weight 68 is connected to the throttle valve control lever 20 by the coupling member 66. The operator then returns to a remote station having suitable circuit actuating means, such as a pair of palm buttons (not shown) as conventionally provided as a safety measure. The operator depresses the palm buttons and a machining cycle is initiated by actuation of the clamping cylinder 46 which moves the carburetor clamp jaw 52 toward the bracket 58. The throttle valve housing 12 is thereby clamped against the support plate 60 and over the guide shaft 62 in clamped position between the bracket 58 and the clamping jaw 52. After the throttle housing is clamped in place, the motor means 30 is actuated to move the slide 24 forwardly toward the locating gauge 80. The slide 24 advances a relatively short distance until the contact 96 engages the limit switch 90 to de-energize the motor means 30. Actuation of the limit switch 90 causes energization of the motor 36 and engages a high speed clutch in the clutch mechanism 38 to drive the slide 34 forwardly toward the locating gauge 80 relative to the slide 24 at a high rate of speed. As the housing 12 is moved adjacent the locating gauge 80, the probe 84 extends into the induction passage 14 and eventually engages the throttle valve 16. A first set of contacts in the locating gauge are actuated by movement of the probe 84 due to engagement with the throttle valve when the housing 12 is approximately .0015 inch from a predetermined position relative to the machine head 22. Actuation of the first set of contacts causes the high speed clutch to be disengaged and causes a low speed clutch of the clutch mechanism to be engaged to drive the slide 34 forwardly at a decreased rate of speed of approximately .001 inch per second. When the carburetor body reaches the predetermined position relative to the machining head 22, a second set of contacts in the locating gauge are actuated by the further depression of the probe 84 which is in continued engagement with the throttle valve 16. Actuation of the second set of contacts disengages the low speed clutch and energizes the brake mechanism to exactly position the valve housing 12 relative to the machine head 22 in relation to the closed position of the carburetor throttle valve. After suitable time delay means provided in the circuitry times out, a signal is generated to actuate the cylinder 74 and move the carburetor throttle valve 16 to an open position against the bias of the weight 68. As shown in FIGURE 4, the guide shaft 62 is provided with a relieved surface 64 to accommodate opening movement of the throttle valve 16. It is necessary to move the throttle valve to an open position to avoid damage thereto during the machining operation. The signal generated after the time delay also causes the machining head 22 to be actuated into cutting engagement with the carburetor body to machine a hole or holes through the carburetor body and into the induction port. It is to be noted that the location of the machined hole or holes will be exactly spaced relative to the carburetor throttle valve and to a particular position thereof in all of the carburetors produced regardless of variation in throttle valve housing dimensions and locations of relative parts. After the machining operation is completed, the machining heads 22 are retracted and the motor means 30 is actuated to retract the slide 24 and thereby actuate the limit switch 92. Actuation of the limit switch 92 generates a signal which actuates the clamping cylinder 46 to retract the clamping jaw 52, reverses the motor 36, energizes the high speed clutch in the clutch mechanism 38 to return the slide 34 to the starting position, actuates the cylinder 74 to a retracted position and re-sets the timer mechanism to prepare the apparatus for another machining cycle. The limit switch 94 is provided to prevent a jam condition occur-

ring between the slide 34 and the rear portion 28 of the slide 24.

Although the present invention is particularly advantageous in the machining of carburetors, the method and apparatus disclosed are adaptable for use with other types of workpieces which have a movable reference surface from which other portions of the workpiece are to be located. In addition, the method and apparatus disclosed are also adaptable for location of a variety of workpieces from a fixed reference surface in the aforescribed manner. Therefore, obvious modifications and re-arrangements of the apparatus described are intended to be included within the scope of this invention as defined by the appended claims, except insofar as limited by the prior art.

We claim:

- Apparatus for machining a device, such as a carburetor or the like, having a cavity and a movable reference surface located therein, a control shaft connected to said movable reference surface and having portions extending outwardly from said cavity, coupling means fixed to said portions, a support frame, a gauge bracket fixed to said support frame and extending upwardly therefrom, a lower slide, said lower slide being movably supported on said frame adjacent said gauge bracket being movable from a position adjacent said gauge bracket to a position spaced outwardly away therefrom, motor means to actuate said lower slide between said positions, an upper slide movably supported on said lower slide, drive means fixably mounted on said lower slide and connected to said upper slide for sliding actuation thereof relative to said lower slide, a clamping bracket fixed to one end of said upper slide, a clamping cylinder supported on said upper slide, a carburetor clamping jaw spaced from said clamping bracket and connected to said clamping cylinder for actuation thereby between an open position and a clamped position whereat a carburetor is fixedly secured between said clamping bracket and said clamping jaw, a guide shaft fixed to said clamping bracket, said guide shaft being contoured to extend within said cavity of said carburetor when said carburetor is in said clamped position, said guide shaft being spaced from said movable surface a sufficient distance to permit movement thereof when said carburetor is in said clamped position, control means to engage said coupling means of said control shaft to bias said movable surface to a predetermined position, locator gauge means mounted on said gauge bracket, a movable probe extending outwardly from said locator gauge means towards said carburetor and being aligned with said cavity in said carburetor in said clamped position, said clamping bracket and said guide shaft being apertured to receive said probe therethrough, said probe being positionable within said cavity to engage said movable surface during movement of said upper slide, a plurality of contacts provided by said locator gauge means and being actuatable by movement of said probe to control said drive means, machining apparatus supported adjacent said carburetor in said clamped position, and said probe being positioned relative to said machining apparatus and said movable surface to cause actuation of said contacts by engagement of said probe with said movable surface to stop said drive means when said carburetor has reached a predetermined position relative to said machining apparatus for a machining operation thereon.
- Apparatus for machining a device, such as a carburetor or the like, having a cavity and a movable reference surface located therein, a control shaft connected to said movable reference surface and having portions extending outwardly from said cavity, a support frame, a lower slide movably supported on said frame and being slidable thereon, motor means to actuate said lower slide, an upper slide movably supported on said lower slide and being slidable relative thereto, drive means fixably mounted on said lower slide and connected to said upper slide for sliding actuation thereof relative to said lower slide, clamping means supported on said upper slide and

being movable from an open carburetor-receiving position to a clamped carburetor-holding position, a locating gauge, a gauge support bracket fixably supported adjacent said upper slide, movable probe means actuably connected to said locating gauge and being aligned with a portion of said movable reference surface and extending into the path of movement of said carburetor on said upper slide, positioning means coupled to one of said portions of said control shaft to bias said movable reference surface to a predetermined position, a plurality of contacts associated with said locating gauge and being actuatable by movement of said probe to control said drive means, machining apparatus supported adjacent said upper slide, and said probe being positioned relative to said machinery apparatus and to said movable surface to cause actuation of said contacts by engagement of said probe with said movable surface to stop said drive means when said carburetor has reached a predetermined position whereat said movable reference surface in said predetermined position is spaced a predetermined distance from said machining apparatus for a machining operation thereon.

- 5 3. The apparatus as defined in claim 2 and having servo-motor means connected to another of said portions of said control shaft, and said servo-motor means being actuably connected and responsive to said locating gauge and actuatable thereby by actuation of said contacts to reposition said movable surface after said carburetor has reached said predetermined position thereof to prevent interference between said movable reference surface and said machining apparatus during the machining operation.
